UNITED STATES PATENT OFFICE

2,588,693

SMOKING PIPE

Sherman F. Bowles, San Antonio, Tex.

Application August 17, 1946, Serial No. 691,304

3 Claims. (Cl. 131—184)

1

This invention relates to new and useful improvements and structural refinements in smoking pipes, and the principal object of the invention is to provide a device of the character herein described, which embodies in its construction means for preventing moisture from reaching the mouth of the smoker and further means for preventing the obstruction of the pipe stem by particles of tobacco.

A further object of the invention is to provide a smoking pipe in which the stem may be easily kept clean.

Another object of the invention is to provide a cleaning and filtering device which may be readily associated with smoking pipes of various sizes and types.

An additional object of the invention is to provide a device of the character herein described, which is simple in construction and which will readily lend itself to economical manufacture.

With the above more important objects in view, and such other objects as may become apparent as this specification proceeds, the invention consists essentially of the arrangement and construction of parts as illustrated in the accompanying drawings, in which:

Figure 1 is a cross-sectional view of a pipe, showing the invention in situ therein.

Figure 2 is a further cross-sectional view of the pipe bowl and stem portion, illustrating the manner in which the invention is used for cleaning the same.

Figure 3 is a cross-sectional view of the cleaning member per se.

Figure 4 is a cross-sectional view of a tube used in the invention.

Figure 5 is an end view, taken in the direction of the arrow 5 in Figure 3; and

Figure 6 is a side elevational view of the pipe mouthpiece.

Like characters of reference are used to designate like parts in the specification and throughout the several views.

Referring now to the accompanying drawings in detail, the invention embodies in its construction a tube 10, internally threaded at one end thereof as at 11, while its remaining end portion is removably receivable in a counterbore 12 formed in the bore 13 of the pipe mouthpiece 14.

This mouthpiece is provided with an adaptor 15, removably receivable in the bore 16 of the stem portion 17, the latter being, of course, associated with the bowl 18. It will be noted that the threaded end portion of the tube 10 extends into the bore 16 in a spaced relation therewith, as is best shown in Figure 1.

2

A cleaning member designated generally by the reference character 19 consists of a cylindrical body 20 provided at one end thereof with a substantially frusto-conical head 21, while the remaining end is equipped with a shank of reduced diameter, as at 22. The free end portion of the shank 22 is externally threaded as at 23, the purpose of which is hereinafter more fully explained. It will be noted in Figure 1 that the tube 10 normally projects outwardly from the end of the stem a distance greater than the spacing of the adjacent ends of the shank and the tube.

The member 19 is formed with a longitudinally extending, axial smoke passage 24, and the head 21 is provided with radially disposed smoke channels 25. It will be noted that the smoke channels communicate with the passage 24.

The body 20 is removably receivable in the bore 16 of the stem 17, said bore being formed at the entry thereof into the bowl 18 with a frusto-conical seat 26. When the member 19 is inserted in position, the head 21 thereof will engage the seat 26, as shown in Figure 1.

When the invention is placed in use, the device 19 is arranged as shown in Figure 1, wherein it will be apparent that the position of the smoke channels 25 and the passage 24 in the head 21 will tend to prevent particles of tobacco in the bowl 18 from moving to obstruct the flow of smoke between the bowl and the bore 16.

The smoke will, of course, travel through the channels 25 and the passage 24 into the bore 16 and then through the tube 10 and the mouthpiece 14, more specifically, through the bore 13 of the mouthpiece, into the mouth of the smoker. It will be noted in this connection, that any moisture such as may be present in the smoke will be collected in the bore 16 by virtue of the spaced relationship of the tube 10 with respect to said bore.

When it is desired to clean the bore 16, the mouthpiece 14 is separated from the stem portion 17 in the conventional manner, and the tube 10 is withdrawn from the counterbore 12.

The threaded portion 11 of the tube may then be engaged with the threaded portion 23 of the member 19, whereby said member may be easily and conveniently withdrawn from the bore 16, as is best shown in Figure 2. During this withdrawing operation, any sediment such as may be present in the bore will be effectively removed as indicated at 27.

It is believed that the advantages and use of the invention will be clearly apparent from the foregoing disclosure and accordingly, further de-

scription thereof at this point is considered unnecessary.

While in the foregoing there has been shown and described the preferred embodiment of this invention it is to be understood that minor changes in the details of construction, combination and arrangement of parts may be resorted to without departing from the spirit and scope of the invention as claimed.

What I claim as my invention is:

1. A smoking pipe comprising in combination, a bowl and stem portion formed with a longitudinally extending bore, a mouthpiece separably connected to said stem portion and provided with a continuation of said bore, a tube removably received in the bore of said mouthpiece and projecting into the bore of said stem portion in concentric spaced relation thereto, and a cleaning member comprising a shank disposed in spaced concentric relation in the bore, said shank being provided with a substantially frusto-conical head slidably fitted in the bore, said bore being formed with a seat adjacent the entry thereof into said bowl, said head and shank having a longitudinal bore therethrough, said head being engageable with said seat, said head being provided with a plurality of smoke passages, said tube and the shank being spaced from each other and having means carried on their adjacent ends for detachably coupling together, said tube projecting a greater distance beyond the end of the stem portion remote from the bowl than the shank and the tube are spaced apart.

2. In association with a smoking pipe, a cleaning and filtering device comprising in combination, a tube screw threaded at one end thereof and removably received at its remaining end in the mouthpiece of the pipe, the screw threaded end portion of said tube extending into the bore of the pipe stem in a spaced relation therewith, and a cleaning member comprising a cylindrical body slidably fitted in the bore and having a substantially frusto-conical head at one end and a threaded shank of reduced diameter at the remaining end of said body projecting in spaced relation to the bore towards the tube, said body, said head and said shank being formed with a longitudinally extending smoke passage, said head being provided with radial smoke channels communicating with said passage, said body being removably receivable in the bore of said stem with said head partially closing the opening of said bore into the pipe bowl, the shank and the

tube being normally spaced apart with the adjacent end of the shank being threaded complementary to the threaded end of the tube, whereby the tube and the shank are adapted to be detachably coupled together so that the shank and the body may be drawn through the bore by the tube.

3. A smoking pipe comprising, a pipe bowl provided with a stem having a longitudinally extending bore therethrough communicating with the interior of the bowl, a mouthpiece detachably secured to the end of the stem remote from the bowl, said mouthpiece having a longitudinal bore therethrough opening into the bore in the stem, a pipe stem cleaning member comprising a head slidably fitted into the bore in the stem and normally positioned closely adjacent the bowl, a shank on said head and supported solely thereby projecting in spaced concentric relation to the stem towards the mouthpiece, said head and shank having a smoke passage therethrough, a tube removably received in the bore of the mouthpiece and projecting in spaced concentric relation to the stem towards the shank, said tube being supported solely by the mouthpiece and terminating in spaced relation to the shank, the adjacent ends of the shank and the tube having complementary screw threads for coupling together, said tube normally projecting outwardly from the end of the stem remote from the bowl a greater distance than the spacing of the shank and the tube, whereby the mouthpiece may be removed from the stem and the tube disconnected from the mouthpiece and the tube reinserted in the stem by itself and coupled to the shank for withdrawing the head from the stem.

SHERMAN F. BOWLES.
